CLAIM

The ornamental design for a building control module, as shown and described.

DESCRIPTION

FIG. 1 is a perspective view of a building control module with an antenna along the top side in a first position; FIG. 2 is a perspective view of a building control module with the antenna rotated into a second position;

FIG. 3 is a front elevation view of the building control module of FIG. 2;

FIG. 4 is a left side view of the building control module of FIG. 2;

FIG. 5 is a right side view of the building control module of FIG. 2;

FIG. 6 is a top plan view of the building control module of FIG. 2; and,

FIG. 7 is a bottom plan view of the building control module of FIG. 2;

(Continued)

The portions illustrated in broken lines on the figures are for illustrative purposes only and form no part of the claimed design.
